DESIGN FOR A PLASTIC BELT

Kenneth Krasnow, New York, N. Y.

Application April 21, 1948, Serial No. 145,879

Term of patent 3½ years

(Cl. D3—10)

To all whom it may concern:

Be it known that I, Kenneth Krasnow, a citizen of the United States, residing at New York, in the county of the Bronx and State of New York, have invented a new, original, and ornamental Design for a Plastic Belt, of which the following is a specification, reference being had to the accompanying drawing, forming part thereof.

Fig. 1 is an elevational view of a plastic belt, showing my new design.

Fig. 2 is a sectional view taken on the line 2—2 of Fig. 1.

The two lines of V-shaped configurations are embossed in the bottom face of the belt.

I claim:

The ornamental design for a plastic belt, as shown and described.

KENNETH KRASNOW.
